UNITED STATES PATENT OFFICE

EVERETT WORTHINGTON, OF CHICAGO, ILLINOIS, ASSIGNOR TO THE CROSLEY RADIO CORPORATION, OF CINCINNATI, OHIO, A CORPORATION OF OHIO

DESIGN FOR A RADIOCABINET

Application filed October 17, 1930. Serial No. 37,299. Term of patent 8½ years.

To all whom it may concern:

Be it known that I, EVERETT WORTHINGTON, a citizen of the United States, and a resident of Chicago, in the county of Cook and State of Illinois, have invented a new, original, and ornamental Design for a Radiocabinet, of which the following is a specification, reference being had to the accompanying drawing, forming part thereof.

In the drawing:

Figure 1 is a perspective view of the cabinet with the doors open.

Figure 2 is a perspective view of the cabinet with the doors closed.

I claim:

The ornamental design for a radiocabinet, as shown.

EVERETT WORTHINGTON.
